INDICATING LAMP

Charles P. West, Forest Hills, Pa., assignor to
Westinghouse Electric & Manufacturing Com-
pany, East Pittsburgh, Pa., a corporation of
Pennsylvania

Application February 26, 1941, Serial No. 380,680

10 Claims. (Cl. 177—329)

My invention relates, generally, to indicating lamps and it has reference, in particular, to a panel mounting indicating lamp unit.

Generally stated, it is an object of my invention to provide an indicating lamp unit for panel mounting which is of simple and rugged construction and which may be economically manufactured and installed.

More specifically, it is an object of my invention to provide an indicating lamp and resistor unit of the panel mounting type which is so constructed that it may be readily mounted on panels of widely different thickness, including both metal and slate panels.

A further object of my invention is to provide a switchboard indicating lamp unit which may be mounted in an opening in the switchboard panel and which is readily adjustable to a relative variation in panel thickness.

Another object of my invention is to provide for detachably securing a lens to a lamp receptacle.

Yet another object of my invention is to provide for securing a lamp resistor about, or in end-to-end relation with, a lamp receptacle which projects through an opening in the panel to permit the use of one size of lamp receptacle with a wide range of panel thickness.

Still another object of my invention is to provide for securing an indicating lamp resistor to an indicating lamp receptacle mounted in a panel opening so as to accommodate a relatively wide range of panel thickness and occupy only a minimum of space to the rear of the panel.

Other objects will, in part, be obvious and will, in part, appear hereinafter.

In accordance with my invention, the panel mounting indicating lamp unit may comprise a lamp receptacle comprising an elongated body portion disposed to project through a panel opening and having a flange at one end for positioning the body portion in the opening. The lamp resistor, which is used to reduce the voltage applied to the lamp, may be provided with an axial opening sufficiently large to receive the body portion of the receptacle. When the indicating lamp unit is mounted on a relatively thin panel, the resistor may be secured in telescoping relation with the body portion of the receptacle to the rear of the panel. When the indicating lamp unit is mounted on a relatively thick panel so that there is insufficient space on the body portion of the receptacle projecting therethrough to accommodate the resistor, it may be secured to the body portion of the re-

ceptacle in end-to-end relation by means of a threaded stud secured to a terminal at the rear end of the body portion.

For a more complete understanding of the nature and scope of my invention, reference may be had to the following detailed description, together with the accompanying drawing, in which:

Figure 1 is a view, in section, of an indicating lamp unit embodying the principal features of my invention;

Fig. 2 is a side elevational view of the indicating lamp unit of Fig. 1 illustrating an alternate method of securing the lamp resistor to the receptacle;

Fig. 3 is a cross sectional view taken along the line III—III of Fig. 1;

Fig. 4 is a cross sectional view taken along the line IV—IV of Fig. 1;

Fig. 5 is a cross sectional view of the receptacle taken along the line V—V of Fig. 1;

Fig. 6 is a cross sectional view of the receptacle taken along the line VI—VI of Fig. 1;

Fig. 7 is an enlarged front elevational view of the lens unit.

Fig. 8 is an enlarged side elevational view partly in section, of the lens unit;

Fig. 9 is an enlarged rear elevational view, partly in section, of the lens unit;

Fig. 10 is a rear elevational view of a resistor support member; and

Fig. 11 is a side elevational view of the resistor support member of Fig. 10.

Referring particularly to Figs. 1 and 2 of the drawing, the reference numeral 10 denotes, generally, an indicating lamp unit comprising a receptacle 12 for an indicating lamp 13 provided with a lens unit 14 and a lamp resistor 15 for reducing the voltage applied to the indicating lamp. As shown, the indicating lamp unit 10 is disposed to be mounted on panels 16 and 17 which are of greatly different thickness, and project through openings 18 and 19 therein, respectively.

Referring to Figs. 1, 3, 4, 5 and 6, it may be seen that the lamp receptacle 12 may, for example, comprise an elongated body member or portion 20 of a suitable insulating material, such as a phenolic resin, hard rubber or the like, having a recess or opening 22 therein from one end to receive the indicating lamp 13. Suitable means, such as the flanged face plate 24, may be provided about the opening to position the receptacle against the face of the panel 16. The face plate 24 may be secured to the body

member 20 in any suitable manner, being, for example, molded integral therewith. Oppositely positioned slots 25 may be provided in the body member adjacent the face plate, connecting with the recess 22.

In order to provide for making electrical connections to the indicating lamp 13 within the body portion 20 of the receptacle, suitable means, such as the resilient contact members 26 and 28, may be utilized. The contact members may be positioned in oppositely disposed longitudinal grooves 29 and 30 on the outer surface of the body member 20 which connect with the opening or recess 22. The contact members 26 and 28 may be secured by means of screws 31 to suitable terminal bushing members 32 and 33 which may be molded in the body member 20 and positioned in the groove 29 and at the rear end of the body member 20, respectively.

In order to provide for positioning the lamp resistor 15 with respect to the receptacle 12 when the indicating lamp unit is mounted on a relatively thin panel, such as the panel 16, the lamp resistor 15, which may be of any suitable type comprising, for example, a tubular refractory body member 34 having the resistance element (not shown) permanently molded therein and provided with an opening 35 therethrough sufficiently large to receive the body portion 20 of the receptacle. The outer surface of the receptacle 20 may be provided with threads 36 and the nut 37 positioned thereon to both secure the body member 20 to the panel 16 and secure the lamp resistor 15 to the body member 20. The lamp resistor 15 may be connected in series circuit relation with the lamp 13 by means of a conductor 38 connected to the terminal bushing member 32 of the receptacle. Electrical connections to the lamp 13 may then be made to the terminal bushing member 33 of the receptacle and the terminal member 39 of the lamp resistor.

When the indicating lamp unit is to be mounted on a relatively thick panel such as, for example, the panel 17, as shown in Fig. 2, it will be seen that little of the body member 20 of the receptacle 12 projects through the panel. In this instance, the body member 20 may be secured to the panel 17 by means of a single nut 37 positioned on the threaded surface of the body member, and the lamp resistor 15, instead of being mounted about the body member 20, may be positioned in end-to-end relation thereto.

For this purpose, suitable means such as the resistor support members 42, which are shown most clearly in Figs. 10 and 11, may be provided. The support members 42 may, for example, comprise substantially circular disks having central openings 43 with a plurality of fingers 44 bent to project at substantially right angles to the flat surface of the support member on one side. The fingers 44 may be so spaced as to be positioned within the opening 35 of the lamp resistor 15 to center the lamp resistor with respect to the openings 43. The resistor 15 may then be secured to the body member 20 by means of the threaded stud 45, which extends through the opening 35 of the lamp resistor 15 and is threaded into the terminal bushing member 33 at the rear end of the body member 20. The conductor 38 may be connected to the terminal bushing member 32 of the receptacle 12 and electrical connections made to the indicating lamp by means of the terminal member 39 of the lamp resistor and a terminal member 46 on the threaded stud 45.

Referring to Figs. 1, 7, 8 and 9, it will be seen

that the lens unit 14 may comprise a lens member 48 which is disposed to be positioned in the opening or recess 22 of the body portion 20 by means of the resilient fingers 49. The resilient fingers 49 may be associated with the lens member 48 in any suitable manner, being, for example, portions of a spring clip 50 which may be attached to the lens member 48 by suitable means such as, for example, the frame member 52. The spring clip 50 may comprise a hollow rectangular frame portion 54 of a suitable spring material conforming to the shape of the lens member and having the fingers 49 projecting therefrom on opposite sides in the manner shown. The spring clip 50 may be positioned against the rear face of the lens member 48 and secured thereto by means of the inturned edge portions 55 of the metal frame member 52. The lens unit 14 may then be positioned in the opening 22 by pressing the unit inwardly until the fingers 49 engage the recesses formed by the openings or slots 25 in the body member 20 adjacent the face plate 24.

From the above description and the accompanying drawing, it will be apparent that I have provided an indicating lamp unit of relatively simple construction whereby a single size of receptacle may be used with a relatively wide range of panel thickness. By positioning the lamp resistor 15 on the body portion of the receptacle 20 when it is used with relatively thin panels and in end-to-end relation thereto when the receptacle is mounted on a relatively thick panel, the same indicating lamp unit may be used with a relatively wide range of panel thickness and yet occupy only a minimum of space to the rear of the panel. The lens unit may be readily attached and removed, and comprises a minimum of parts.

Since different embodiments of the invention may be made and certain departures may be made from the description hereinbefore set forth without departing from the spirit and scope of the invention, it is intended that all the matter contained in the above description or in the accompanying drawing shall be considered as illustrative and not in a limiting sense.

I claim as my invention:

1. An indicating lamp receptacle comprising an elongated body member of insulating material having a threaded surface portion extending substantially throughout its length with a flange integral therewith at one end and an opening therein for receiving a lamp, a pair of oppositely positioned longitudinal grooves in the body member opening into the said opening, a nut member positioned about the body member engaging the threaded portions and resilient contact members positioned within the grooves to engage the lamp for conducting current thereto.

2. An indicating lamp comprising, a lamp receptacle having an exteriorly threaded elongated body portion of insulating material with an integral flange at one end and an opening at the flange end to receive a lamp, longitudinal grooves on the outer surface of the body member connecting with the opening, contact members recessed within the grooves to connect with the lamp, and a lamp resistor detachably secured on the body portion about the contact members and connected to one of the contact members.

3. A panel type indicating lamp unit comprising, a flanged lamp receptacle having a body portion disposed to project rearwardly through an opening in a panel and having an opening therein for receiving an indicating lamp, a tubular resistor to reduce the voltage applied to the

lamp having an opening therethrough to receive the body portion of the lamp, and means for positioning the resistor on the body member.

4. An indicating lamp unit comprising, a lamp receptacle of insulating material having a flanged end portion and an elongated body portion disposed to be inserted through an opening in a panel provided with a central recess therein and longitudinal grooves on the outer surface connecting with the recess, resilient contact members to conduct current to the lamp recessed within the grooves, a resistor for reducing the voltage applied to the lamp having an opening therethrough larger than the body portion of the receptacle to permit positioning the resistor about the body portion when the unit is used with a relatively thin panel, and means for mounting the resistor in end-to-end relation with the body member when the unit is used with a relatively thick panel.

5. A panel mounting indicating lamp unit comprising, a lamp receptacle having a body portion with a central opening at one end to receive a lamp and a flange about the opening to position the receptacle in a panel opening, a pair of oppositely disposed longitudinal grooves on the outer surface of the body portion connecting with the central opening, a terminal member positioned at the other end of the body portion, an additional terminal member positioned in one of the grooves, resilient contact members connected to the terminal members recessed in the grooves and projecting into the central opening to contact with the lamp terminals, and a resistor disposed to be connected to one of the terminals having a central opening to receive the body portion of the receptacle, said resistor and body portion being arranged so that the resistor may be positioned about the body portion when the receptacle is used with a relatively thin panel and may be positioned in substantially end on relation with the body portion when the receptacle is used with a relatively thick panel.

6. An indicating lamp comprising, a body member of insulating material having an opening therein from one end for a lamp and a flange integral with said end of the body member, a terminal member at the other end, a pair of opposed longitudinal surface grooves on the body member connecting with the opening, an additional terminal member recessed within one of the grooves, contact members connected to the terminal members positioned within the grooves and extending into the opening, means to secure the body member to a panel positioned about the body member, a lamp resistor, and means for mounting the lamp resistor on the end terminal member in end-to-end relation with the body member.

7. An indicating lamp receptacle comprising, an elongated body member having a substantially continuous threaded outer surface for receiving means whereby the receptacle may be mounted on a relatively thick panel or a thin one at one end to receive a lamp, a flanged face plate integral with the body member at said one end, oppositely

disposed longitudinal grooves on the outer surface of the body connecting with the said opening, a terminal member formed in the body member at the other end, an additional terminal member positioned in one of the grooves adjacent said other end, and resilient contact members connected to the terminal members recessed within the grooves and extending into the opening.

10. A universal indicating lamp for use with relatively thick or relatively thin panels having openings therein comprising, an elongated lamp receptacle positionable in the opening having a threaded body portion sufficiently long to project beyond a relatively thick panel with a flange at one end to position the receptacle relative to the front of the panel and a terminal member at the other end, a tubular resistor for connection to a lamp in the receptacle having an opening therethrough of sufficient size to receive the body portion, means to support the resistor on the terminal member when the unit is used with a relatively thick panel, and means for mounting the resistor on the body member between the panel and the terminal member when the unit is used with a relatively thin panel.

15. An indicating lamp unit for mounting in an opening in a relatively thick or a relatively thin panel comprising, an elongated lamp receptacle of insulating material having a threaded body portion of sufficient length to project through the opening in a relatively thick panel with means at one end to position the unit relative to the panel front, means positionable on the body portion intermediate the ends to secure the body portion in the panel opening, and a tubular resistor having an opening therethrough sufficiently large to receive the body portion, said body portion being arranged to support the resistor in substantially end to end relation at the rear of the panel when the body portion is mounted on a relatively thick panel and intermediate the ends of the body portion when it is mounted on a relatively thin panel.

20. An indicating lamp for use with relatively thick panels or relatively thin panels having openings therethrough comprising, an elongated lamp receptacle having a body portion of sufficient length to project through the opening in a relatively thick panel with means at one end to position the body portion relative to the front of the panel and a terminal member at the other end, means positionable on the body portion intermediate the ends to secure the body portion in the panel opening, and a resistor for connection in series with a lamp in the receptacle arranged to be mounted in substantially end to end relation with the body portion on the terminal member when the body portion is used with a relatively thick panel, said resistor having an opening therethrough for receiving the body portion and being of such a length as to be positionable on the body portion between the panel and the terminal member when the body portion is used with a relatively thin panel.

CHARLES P. WEST.
